United States Patent Office.

WILLIAM H. DUTTON, OF PHILADELPHIA, PENNSYLVANIA.

Letters Patent No. 76,423, dated April 7, 1868.

IMPROVED CABINET-BEDSTEAD.

The Schedule referred to in these Letters Patent and making part of the same.

TO ALL WHOM IT MAY CONCERN:

Be it known that I, WILLIAM H. DUTTON, of Philadelphia, in the county of Philadelphia, and State of Pennsylvania, have invented a new and improved Cabinet-Bedstead; and I do hereby declare that the following is a full, clear, and exact description thereof, which will enable those skilled in the art to make and use the same, reference being had to the accompanying drawings, forming part of this specification.

This invention relates to a new and useful improvement in that class of bedsteads which are constructed so as to fold upward, and be concealed from view when not in use, and present the appearance of a book-case, or other piece of furniture generally used in sitting or reception-rooms.

The invention consists in an improved manner of hanging the bedstead, as hereinafter fully shown and described, whereby the bedstead may be counterpoised, so as to require but a slight effort to raise and lower it.

The invention further consists in a novel application of legs or supports to the bedstead, as hereinafter fully shown and described, whereby the legs or supports will be automatically folded and unfolded by the raising and lowering of the bedstead, and in such a manner as not to interfere in the least with the application of the hands in manipulating the bedstead. In the accompanying sheet of drawings-

Figure 1 is a side view of my invention in a folded state.

Figure 2, a side sectional view of the same in an unfolded state, taken in the line *xx*, fig. 3.

Figure 3, a transverse section of the same, taken in the line *yy*, fig. 2.

Similar letters of reference indicate corresponding parts.

A represents a frame or case, in which the bedstead, *B*, is hung, and of sufficient dimensions to receive and enclose the bedstead, when the same is folded or turned up, as shown in fig. 1. This frame or case may be made in a suitable manner, so as to have a chaste and neat appearance, and to imitate, if desired, a book-case, wardrobe, or other piece of furniture.

The bedstead, *B*, may be of the ordinary quadrilateral form, having a head and foot-board, *a b*, and two side-pieces, *c c*. The bottom of the bedstead, in consequence of being exposed when the bedstead is folded upward within the frame or case, and forming the front of the device, should be made in a neat manner, and may have mirrors or glasses inserted in it, and lined with "reps," to imitate a book-case. I do not confine myself, however, to any particular mode of constructing the bedstead-bottom.

The head-board, *a*, of the bedstead is made quite heavy, or has a weight attached, to serve as a counterpoise, and to each side of the bedstead, near the head-board, there is permanently attached a curved bar, *C*, to one end of each of which, one end of a strap, *D*, is attached, the opposite ends of the straps being attached to the frame or case *A*, as shown at *d* in fig. 2.

By means of these straps *D* and curved bars *C*, the bedstead, as it is raised and lowered, moves from or on a variable or shifting-fulcrum, the latter always being at the point on the bar *C* where the straps *D* leave them, and these curved bars *C* are attached to the sides of the bedstead in such a position that, as the bedstead is raised, the weight or counterpoise *a* (the head-board) will act efficiently, or never vary or become inoperative or inert, as would be the case were the bedstead hung upon a fixed axis, for, in the latter case, the weight or counterpoise ceases to act as it passes underneath the axis.

In my improvement, the weight or counterpoise never passes underneath the axis or fulcrum, but always remains in a line at one side of it, so as to have a tendency to keep the bedstead, when elevated, in an elevated state, and, at the same time, not increase in efficiency as the bedstead is lowered, so as to cause much effort on the part of the operator in thus adjusting the bedstead. The design is to have the bedstead as nearly equilibrated as possible, so that when the bedding is placed on the latter, the preponderance of weight will have a tendency to keep the bedstead in a horizontal position, when in use, and when raised or not in use, have a tendency to keep it raised or in a closed state. This result can only be obtained by a shifting or variable fulcrum, arranged to operate substantially as described.

E E represent the legs of the bedstead, which are pivoted to the foot-board *b*, the application of legs to the foot-board being only required, as the straps *D* support the opposite end of the bedstead. The pivots or axes, *e*, of these legs have coil-springs, *f*, connected to them, which have a tendency to keep them spread apart, parallel

with each other, and at right angles with the foot-board *b*, the portion to support the foot of the bedstead when the bedstead is down or adjusted for use, as shown in fig. 2.

The portion of each leg *E* around the pivots or axes *e* is cylindrical, so as to form a pulley, *f* $\times$, concentric with the axes, and these pulleys *f* $\times$ have each a cord, *g*, attached, and these cords pass through the foot-board *b*, and are both connected to a common cord, *h*, which passes through the head-board *a*, and is attached to the rear part of the frame or case *A*, as shown at *e'*.

These cords *g*, *g*, and *h* perform an important function, to wit, they draw inward or fold the legs *E* *E* on or over the foot-board *b*, when the bedstead is raised, but said cords do not immediately act when the bedstead is first raised, on account of the cords *g* *g* *h* being slack when the bedstead is down, but when the bedstead has reached a certain degree of elevation, the cords tighten, on account of the head, *a*, of the bedstead acting upon cord *h*, and the legs *E* *E* are drawn inward under the influence of the cords *g* *g*. The legs *E* *E* are not thus moved until the foot of the bedstead reaches a height above the hand of the operator, or after it is necessary for the operator to remove his hand from the top. The movement of the legs, therefore, it will be seen, does not interfere in the least with the manipulating of the bedstead.

There is an important result obtained by this automatic movement of the legs, in connection with the raising and lowering of the bedstead, and that is the controlling, in a certain degree, by means of the coil-springs, of the legs, the movement of the bedstead at the termination of its upward movement and at the commencement of its downward movement. The resistance offered by said coil-springs prevents the slamming of the bedstead at the termination of its upward movement, and the strength of the springs, (their tendency to expand or unwind,) serves to aid the starting of the bedstead in lowering it.

I would remark that, as regards the variable or shifting-fulcrum, composed of the curved bars *C* and straps *D*, the same result would be obtained by having the bars *C* toothed, to form racks, and have racks attached to the frame *A*, to gear into *C*. This modification, however, would be more expensive than the one previously described and illustrated.

I would further remark that, in order to steady the movement of the bedstead, I have a roller, *i* $\times$, attached to each end of it, and these rollers bear or work against curved pieces, *j*, within the frame or case *A*, at each side of the lower part of the same, the curvature of the pieces *j* *j* corresponding to the curvature the head-board *a* describes in moving in either direction. This will be fully understood by referring to fig. 2.

I claim as new, and desire to secure by Letters Patent—

1. The straps *D* and curved bars *C*, in combination with the parts *A* *B* of the bedstead, arranged and operating substantially as and for the purpose set forth.
2. The adjusting or moving of the legs *E* *E* automatically, by the raising or lowering of the bedstead, through the media of the coil-springs and cords, arranged substantially as shown and described.

The above specification of my invention signed by me, this fifteenth day of February, 1868.

WM. H. DUTTON.
